(57) **CLAIM**

The ornamental design for a recording jammer as shown and described.

DESCRIPTION

Fig. 1.1 is a perspective view of a recording jammer according to a first embodiment of the present application, showing our new design;

Fig. 1.2 is a front view thereof;

Fig. 1.3 is a rear view thereof;

Fig. 1.4 is a left side view thereof;

Fig. 1.5 is a right side view thereof;

Fig. 1.6 is a top view thereof; and

Fig. 1.7 is a bottom view thereof.

Fig. 2.1 is a perspective view of a recording jammer according to a second embodiment of the present application, showing our new design;

Fig. 2.2 is a front view thereof;

Fig. 2.3 is a rear view thereof;

Fig. 2.4 is a left side view thereof;

Fig. 2.5 is a right side view thereof;

Fig. 2.6 is a top view thereof; and

Fig. 2.7 is a bottom view thereof.

(Continued)

The broken lines depict portions of the recording jammer that form no part of the claimed design.

1 Claim, 14 Drawing Sheets
